UNITED STATES PATENT OFFICE

156,187

DESIGN FOR A RUBBER ROCKING TOY

Arthur Oscar Walker, Harrow, England, assignor
to Playlastic Toy Company Limited, London,
England, a British company

Application October 20, 1948, Serial No. 149,212
In Great Britain April 24, 1948

Term of patent 7 years

(Cl. D34—15)

To all whom it may concern:

Be it known that I, Arthur Oscar Walker, a subject of the King of Great Britain and resident of Harrow, Middlesex, England, have invented a new, original, and ornamental Design for Rubber Rocking Toy, of which the following is a specification, reference being had to the accompanying drawings, forming a part thereof.

Fig. 1 is a front view, and

Fig. 2 is a back view of a rubber rocking toy, showing my design.

I claim:

The ornamental design for a rubber rocking toy, as shown.

ARTHUR OSCAR WALKER.
